UNITED STATES PATENT OFFICE

2,516,961

GUTTER DRAIN

Edward L. Dailey, Priest River, Idaho

Application June 14, 1946, Serial No. 676,684

6 Claims. (Cl. 119—15)

1

My invention relates to drains and more particularly to drains for cow stable gutters.

The object of my invention is to provide a drain for cow stable gutters adapted to drain the water from the solid droppings in the gutter, thereby facilitating the cleaning of the gutters and preventing soiling of the cattle by being splashed with liquids in the gutter.

Another object of my invention is to provide a drain for cow stable gutters having an auxiliary or secondary drain connected therewith to drain the liquid from the solids in the gutter, if the main drain should get clogged.

A further object of my invention is to provide a drain for cow stable gutters adapted to be hingedly attached to the driveway side of the gutter, so that the entire drain unit can be pivoted out of the gutter for cleaning purposes.

Other objects of my invention may appear in the following specification describing my invention with reference to the accompanying drawing illustrating a preferred embodiment of my invention.

It is however to be understood, that my invention is not to be limited or restricted to the exact construction and combination of parts described in the specification and shown in the drawing, but that such changes and modifications can be made, which fall within the scope of the claims appended hereto.

In the drawing:

Figure 1 is a plan view of a plurality of cow stalls provided with a gutter drain according to my invention.

Figure 2 is a sectional view taken on line 2—2 in Figure 1.

Figure 3 is a sectional view taken on line 3—3 in Figure 1, the main drain plate being shown as partly broken away, to show the secondary drain plate, and

Figure 4 is a sectional view similar to Figure 2 illustrating a modification of the drain construction according to my invention, in which the secondary drain plate is permanently embedded in the bottom of the gutter.

Referring now in detail to the drawing a gutter 10 is arranged between the floor 11 of the cow stalls and the floor 13 of the driveway in a cow barn. The bottom 14 of the gutter 10 slopes from the stall side toward the driveway side, as clearly shown in Figures 2 and 4.

A plurality of angular hinge members 15 are firmly fastened onto the edge of the gutter 10 on the driveway side.

2

A main drain plate 16 has on its upper edge another plate element 17 extending at right angles to the drain plate and on this plate element 17 a flange 18 is formed extending at right angles to said element and in the same direction as the main drain plate 16.

The drain plate unit is hingedly attached to the angular hinge members 15 so that the main drain plate 16 extends downwardly into the gutter 10 as shown in Figures 2 and 4. This main drain plate is provided with a plurality of perforations, which are preferably very small and arranged close together so as to permit the liquid contents of the gutter to drain through the main drain plate 16 into the part of the gutter 10 adjacent the driveway. The solid parts of the gutter contents remain in the gutter part between the main drain plate 16 and the stalls.

A secondary drain plate 19 has a flange 20 arranged on its upper edge and extending at right angles therefrom. The flange 20 is firmly fastened to the underside of the plate element 20 in any conventional manner, for instance by welding. The secondary drain plate 19 is provided with a plurality of cut-outs 21 in its lower edge. Preferably the cut-outs 21 have the shape of an inverted V, as shown in Figure 3.

As shown in Figure 4, illustrating a modification of the drain construction according to my invention, a secondary drain plate 22 provided with cut-outs 23 in its lower edge is permanently embedded in the concrete, forming the bottom 14 of the gutter 10, as indicated at 24 in Figure 4. The cut-outs 23 in this plate 22 are also shaped like an inverted V, and extend far enough upwardly to be located above the bottom 14 of the gutter 10. The upper edge of the secondary drain plate 22 in this modification abuts the underside of the plate element 17.

The drain unit is preferably made in sectional units, as indicated at 25, to facilitate the handling of the drain for cleaning purposes. For this purpose the individual units are pivoted about the hinges on the hinge members 15, so that the unit will rest on the floor 13 of the driveway, where it can be cleaned easily. After that it is swung back into working position.

By the use of a gutter drain as described above, the gutter can be cleaned very easily, and splashing of the gutter contents is practically eliminated entirely.

Like all gutters the gutter 10 described above is constructed to drain into a collecting basin or the like located outside the barn.

Having described my invention, I claim as new and desire to secure by Letters Patent:

1. A barn drain construction comprising a gutter arranged between the stalls and the driveway in the barn and sloping to drain out of the barn including a bottom in the gutter sloping downwardly from the stable side to the drive way side, and a main drain plate removably arranged in the gutter and extending longitudinally thereof, and being provided with a plurality of perforations therein, a plate element formed on the upper edge of the main drain plate and extending at right angles thereto, a flange on the edge of the plate element extending downwardly at right angles thereto and hingedly fastened onto the drive way edge of the gutter, and a secondary drain plate having a plurality of cutouts in its lower edge and arranged longitudinally of the gutter between the main drain plate and the drive way side wall of the gutter, and permanently embedded in the bottom of the gutter.

2. A barn drain structure comprising a gutter, a main strainer positioned longitudinally in said gutter and located between the sides of said gutter for straining liquid from a mass of solid and liquid matter placed in said gutter at one side of said strainer plate, and a secondary strainer positioned longitudinally in said gutter and located between said main strainer and the side of the gutter opposite that in which the mass of solid and liquid matter is placed.

3. A barn drain structure comprising a gutter, a main strainer positioned longitudinally in said gutter and located between the sides of said gutter for straining liquid from a mass of solid and liquid matter placed in said gutter at one side of said strainer plate, and a secondary strainer positioned longitudinally in said gutter and located between said main strainer and the side of the gutter opposite that in which the mass of solid and liquid matter is placed, said secondary strainer comprising a longitudinally elongated vertical plate formed with relatively large longitudinally spaced openings in the lower part thereof.

4. A barn drain structure comprising a gutter, a main strainer positioned longitudinally in said gutter and located between the sides of said gutter for straining liquid from a mass of solid and liquid matter placed in said gutter at one side of said strainer plate, and a secondary strainer positioned longitudinally in said gutter and located between said main strainer and the side of the gutter opposite that in which the mass of solid and liquid matter is placed, said secondary strainer comprising a longitudinally elongated vertical plate formed with relatively large longitudinally spaced openings in the lower part thereof, the upper edge of said secondary strainer

plate having a portion supportably connected to a portion of said main strainer plate, whereby said main and secondary strainer plates form a strainer assembly.

5. A barn drain structure comprising a gutter, a main strainer positioned longitudinally in said gutter and located between the sides of said gutter for straining liquid from a mass of solid and liquid matter placed in said gutter at one side of said strainer plate, and a secondary strainer positioned longitudinally in said gutter and located between said main strainer and the side of the gutter opposite that in which the mass of solid and liquid matter is placed, said secondary strainer comprising a longitudinally elongated vertical plate formed with relatively large longitudinally spaced openings in the lower part thereof, said secondary strainer plate having a lower portion supportably mounted on the bottom of the gutter.
- 10 6. A barn drain structure comprising a gutter, a main strainer positioned longitudinally in said gutter and located between the sides of said gutter for straining liquid from a mass of solid and liquid matter placed in said gutter at one side of said strainer plate, and a secondary strainer positioned longitudinally in said gutter and located between said main strainer and the side of the gutter opposite that in which the mass of solid and liquid matter is placed, said secondary strainer comprising a longitudinally elongated vertical plate formed with relatively large longitudinally spaced openings in the lower part thereof, the upper edge of said secondary strainer plate having a portion supportably connected to a portion of said main strainer plate, whereby said main and secondary strainer plates form a strainer assembly, and means hinging said strainer assembly upon the said opposite side of the gutter, whereby said strainer assembly can be swung upwardly out of the gutter.
